UNITED STATES PATENT OFFICE.

HUGO LENTZ, OF BERLIN-HALENSEE, GERMANY.

ARRANGEMENT FOR STARTING INTERNAL-COMBUSTION ENGINES.

1,151,481.

Specification of Letters Patent. Patented Aug. 24, 1915.

Application filed June 3, 1915. Serial No. 32,002.

To all whom it may concern:

Be it known that I, HUGO LENTZ, a subject of the German Emperor, and residing at Berlin-Halensee, Germany, have invented 5 a new and useful Improvement in Arrangements for Starting Internal-Combustion Engines, of which the following is a specification.

My invention relates to a novel arrangement for starting internal combustion engines by the intermediary of a hydraulic gear controlling at the same time the speed of the shaft to be driven, and is characterized in that the pumping motors of the gear 10 are arranged in groups to suit the number of the internal combustion engines connected therewith, and that one of the sets of pumps driven at the beginning drives the remaining sets of pumps together with the internal 15 combustion engines connected therewith, whereupon as soon as the said additional internal combustion engines are normally running the sets of pumps are connected with the set of motors of the gear, the latter then 20 acting as a mere transmission gear between the power engines and the shaft to be driven.

In the accompanying drawings the invention is illustrated by way of example.

Figure 1 shows the arrangement diagrammatically. Fig. 2 is a longitudinal section through the gear, and Figs. 3 and 4 are transverse sections according to the lines A B and C D, respectively, of Fig. 2.

According to Fig. 1 two separate groups 25 a, b of internal combustion engines (such as Diesel-motors) act by means of the shafts a', b' respectively, upon a hydraulic gear c, which may consist, for instance, of valveless pumps made, as shown, like a well-known 30 form of blower with radially adjustable blades. Said gear is driving a third shaft c'. The said hydraulic gear comprises two sets of pumps d, e which are driven independently of one another by the combustion engines a, b coupled with them. Preferably 35 engines a, b and pumps d, e, driven by same, of such power are used that the group b, e shall have twice the output of the other group a, d. The set of motors of the gear 40 driven by one of the sets of pumps, or by both sets, transmits its motion to the shaft c' to be driven, which is coupled with the said set of motors.

As will be seen from Figs. 2 to 4, in the 45 form of construction illustrated the pumps d, e and the set of motors f are arranged

in the same casing c with their axes parallel to one another. The working chambers d', e' of the pumps are on one side connected by a passage g with the working chamber f' of the set of motors, and communicate on the other side with a chamber h with which also the chamber f' is in open connection. In the pressure and suction passages thus formed, controlling valves k, k' 50 and l, l', respectively, are disposed in immediate proximity to the sets of pumps. The said valves consist of two parts to suit the two part set of pumps d, e, the parts k, l controlling the fluid-passage to the pump d, 55 while the parts k', l' control the corresponding passage to the pump e. According to the position of the said parts the working chambers d', e' communicate with the working chamber f' of the set of motors or with 60 the chamber h. Besides the passages described, there are by-pass conduits m disposed laterally in the casing, and being in communication with a chamber n arranged under the controlling members l, l' and extending the whole length thereof.

The operation of the arrangement is as follows: At the state of rest all the valves are open toward the chamber h, the sets of pumps thus being in immediate connection. In this position the smaller power engine a may be started in any known manner, for instance, by means of compressed air. If, now, merely the valves k, l are caused to assume the position shown in Fig. 65 3, the set of motors f is driven and the shaft c' is rotated at low speed. To cut in the larger power engine b all that it is necessary to do is to bring the valves k', l' in the position represented in Fig. 4. Then a part 70 of the pressure liquid from the pump d flows through the passage m into the chamber n, and from there to the working chamber e' of the pumps e to drive same, whereupon the liquid fluid returns through 75 the chamber h to the suction chamber of the pump d. By the admission of the second pump the second power engine is started. This being done, the normal combustion working may begin, the valves k', l' will 80 in such case be adjusted to the same position in which the valves k, l in Fig. 3 are shown. Then also the second pump is driving the set of motors, so that the latter is rotated 85 at high speed. The different speeds of the shaft c' to be driven may be attained in 90 the manner usual with gears of this kind.

The arrangement may, however, be used in such a way that with the state of rest not the set of motors *f* is moved at the beginning but the pump *d* is used directly for 5 starting the larger power engine. To such end the valves are initially brought to assume the position shown in Figs. 3 and 4. The resistance of the set of motors being very great in such case, the whole pressure 10 liquid will be conducted through the passage *m* and the chamber *n* to the second pump *e* so that the second power engine will be started.

Owing to this novel starting arrangement 15 the compressed air plant heretofore necessary for the larger power engine may be dispensed with. This is most advantageous especially in case the arrangement is employed in connection with means for driving 20 vehicles, locomotives and ships by the intermediary of internal combustion engines, as the available space is very small in such events. The invention, furthermore, enables a number of independent power engines to act upon a joint gear, as they may 25 act upon the shaft to be driven without respect to their different outputs.

Instead of two groups of internal combustion engines a suitable number thereof may 30 act upon a gear; in such case the sets of pumps must be accordingly constructed and arranged. With the form of construction shown each set of machines drives one pump made in one part. The pump in connection 35 with a set of machines may, however, be made in several parts, whereby a greater number of different speeds is to be attained. The sets of pumps and the set of motors

may be single or double-acting. It is also to be understood that my invention is not 40 limited to the construction shown in the drawing, and that various changes may be made in the general arrangement and construction of the parts without departing 45 from the invention.

I claim herein as my invention:

1. In an arrangement for starting internal combustion engines, in combination, a hydraulic transmission gear the pumping motors of which are subdivided to suit the 50 number of attached combustion engines, means for driving one of such sets of pumps, means, acted upon by this set of pumps, for driving the other set of pumps and the combustion engines attached to them, and means for connecting the said sets of pumps to the set of motors of the said hydraulic gear.

2. In an arrangement for starting internal combustion engines, in combination, a 60 hydraulic transmission gear the pumping motors of which are subdivided to suit the number of attached combustion engines, means for driving one of such sets of pumps, by-pass channels extending between the pressure chamber of this set of pumps and the suction chamber of another of the said sets of pumps, and valves for controlling such by-pass channels, substantially as set forth.

In testimony whereof I affix my signature 65 in presence of two witnesses.

HUGO LENTZ.
